Primary Examiner—Sandra S. Snapp(74) *Attorney, Agent, or Firm*—Jacobson Holman PLLC(57) **CLAIM**

The ornamental design for a bench, as shown and described.

DESCRIPTION

FIG. 1 is a perspective view of a bench showing my new design.

FIG. 2 is a right side elevational view of the bench of FIG. 1, the left side view being a mirror image thereof.

FIG. 3 is a front elevational view of the bench of FIG. 1.

FIG. 4 is a back elevational view of the bench of FIG. 1.

FIG. 5 is a top plan view of the bench of FIG. 1; and,

FIG. 6 is a bottom plan view of the bench of FIG. 1. The slats of the bench are shown broken-away in the views to indicate indeterminate length.
